(57) **CLAIM**

The ornamental design for a walk behind mower as shown and described.

DESCRIPTION

FIG. 1 is a front perspective view of a walk behind mower, according to the present invention;

FIG. 2 is a front elevational view of the walk behind mower of FIG. 1;

FIG. 3 is a rear elevational view of the walk behind mower of FIG. 1;

FIG. 4 is a left side elevational view of the walk behind mower of FIG. 1;

FIG. 5 is a right side elevational view of the walk behind mower of FIG. 1;

FIG. 6 is a top plan view of the walk behind mower of FIG. 1; and,

FIG. 7 is an enlarged view of a portion of FIG. 2. The dashed lines in the Figures are for environmental purposes only and do not form a part of the claimed design.
